UNITED STATES PATENT OFFICE.

DANIEL McFARLAN MOORE, OF NEWARK, NEW JERSEY, ASSIGNOR TO
MOORE ELECTRICAL COMPANY, OF NEW YORK, N. Y., A CORPORA-
TION OF NEW YORK.

VACUUM-TUBE ELECTRIC APPARATUS.

No. 854,300.

Specification of Letters Patent.

Patented May 21, 1907.

Application filed February 7, 1906. Serial No. 299,886.

To all whom it may concern:

Be it known that I, DANIEL McFARLAN MOORE, a citizen of the United States, and a resident of Newark, in the county of Essex and State of New Jersey, with post-office address 52 Lawrence street, have invented certain new and useful Improvements in Vacuum-Tube Electric Apparatus, of which the following is a specification.

- 10 The present invention relates to vacuum tube, or vapor electric lamps, vacuum or vapor rectifiers, X-ray tubes, vacuum oscillographs, wireless telegraph receivers and other devices which are provided with suitable electric terminals whereby electric energy may be passed through the gaseous contents of the tube for any purpose and which generally may be classified under the head of vacuum tubes.
- 20 The object of my invention is to provide means whereby the gaseous tension or condition within the tube may be automatically kept uniform or constant by the operation of a valve which regulates the flow of a gas or vapor to the tube and is opened to supply more gas when the vacuum within the tube gets higher or the condition or quality of the gas therein changes for any reason, as for instance, by the action of the electric energy 25 upon the gaseous contents.

The invention consists in the novel combination of devices comprising a valve chamber closed by a spring diaphragm and a valve acted upon by said diaphragm and also by a core or other movable portion of an electromagnet whose power varies with changes in the electrical resistance of the gas or vapor in the tube due to changes of gas or vapor tension.

- 40 I have shown my invention as carried out by an organization or combination in which the vacuum tube is operated by alternating currents and the valve is actuated by changes in the magnetic condition of a transformer, the secondary of which supplies energy to the tube. The invention, however, may be carried out in connection with tubes operated by direct currents, an electromagnet of proper kind being used and being 45 connected with the circuit of the tube so as

to feel the effect of any change in resistance between the terminals thereof.

In the accompanying drawings, Figure 1 is a partial side elevation and vertical section of the transformer and valve together with a 55 portion of the vacuum tube. Fig. 2 is a general diagram of circuits and apparatus.

I have shown my invention and described the same as applied to a vacuum tube lamp, although, it is likewise applicable to other 60 vacuum tubes.

1 indicates the vacuum tube lamp and 2 the energy transferring electrodes or terminals thereof through which energy is conveyed to the gaseous contents of the tube 65 from the secondary 3 of the transformer, the primary 4 of which is connected to suitable constant potential alternating current mains 5 as shown in the diagram. The energy may be transferred to the tube by either external 70 or internal electrodes as well understood in the art. The transformer is preferably of the shell type, although, it would be within my invention to use other types or forms of transformer. Air or other gas is supplied to 75 the tube in regulated quantity to keep the gas tension constant through the tube 6 of which there may be as many applied to the tube 1 and at such points as may be found convenient in practice, the flow of gas 80 through said tube being controlled by a valve connection to them or by separate valves as desired.

My present invention is designed more particularly to afford means whereby a gas may 85 be supplied to the tube from a tank or gas holder and for this purpose I employ the construction of valve now to be described in which there is a valve chamber closed by a metallic or spring diaphragm, which spring 90 diaphragm co-operates with the weight of the movable core of the transformer or other movable mass of iron subject to changes in the magnetic condition of the transformer to keep the valve closed.

95 Fig. 8 shows the valve casing or chamber having inserted at its bottom the perforated plug 7 bored centrally and tapered at its upper end where it forms a valve seat for a block or other shaped piece 9 consisting pref- 100

erably of vulcanized rubber. The plug or piece of material 9 forming a movable element of the valve closes the valve port when it rests upon the end of the plug as a seat and 5 closing the top of the valve chamber is a metallic diaphragm 10 which diaphragm is fastened by a washer 11 to the end of a head 13 carrying block 9. The valve chamber or casing is suitably supported by the depending 10 arms or brackets 14 attached to the transformer body. The core or portion of the core 15 of said transformer is made movable and comprises a bundle of wires or laminæ and has the head 13 suitably fastened to it. The weight of the core assisted 15 by the spring of the diaphragm 10 normally keeps the valve closed. Leading from the valve chamber is a tube 16 which is preferably a flexible tube and is coupled as shown 20 to tube 6. Connected to the plug 7 is a tube 17 which may be joined to a tank or cylinder of the gas used in the vacuum tube. Obviously the gas may pass in either direction, *i. e.*, from tube 17 to tube 16 or from tube 16 25 to tube 17 through the valve. In the latter case, the connections to the tank and tube will be simply reversed.

In the operation of the apparatus, the transformer supplies, through its high tension secondary 3, energy suitable for rendering 30 the gaseous contents of tube 1 luminous, and so long as the adjusted tension of gas or air in the tube is maintained, the valve will remain seated. As is well known, there is a 35 critical tension or degree of vacuum in the tube at which the resistance to the passage of electric energy through the gas from one electrode to the other of the tube is at its lowest. If the vacuum increased beyond this critical 40 point, the resistance increases and the current falls. It is preferable to operate the tube below the degree of vapor or gas tension at which the resistance and current change from a decreasing value of resistance and in- 45 creasing value of current to an increasing value of resistance and decreasing value of current, but for economy the degree of vacuum should be maintained as near as possible to the point where the resistance is least, 50 though sufficiently below such point to avoid the possibility of changes of tension extending over to the degree where the resistance will increase with an increase of the vacuum. When then the tension or condition within 55 the tube changes so as to lower the resistance to the passage of the alternating currents from the secondary through the tube, more energy is taken from the mains, the magnetic condition of the transformer 60 changes and an increased pull is exerted upon the core 15 sufficient to overcome the gravity of the same and the action of diaphragm 10 so that the valve will be momentarily and slightly opened. This will permit a small 65 amount of air or other gas to enter the tube 6

and flow to the vacuum tube, thus restoring the gaseous tension or condition therein, whereupon the resistance within the same will rise slightly and the valve will thereupon be permitted to close. By the repeated actions of the valve taking place as changes in the condition of the tube 1 require, a practically constant gaseous condition within the tube will be maintained through the feeding of the gas into the same in minute, adjusted 70 or regulated quantities. As will be seen, my invention enables me to dispense with the use of separate regulating magnets independent of the transformer which is the arrangement described in another application for 80 patent filed by me, whereby I combine in one instrument both the means for supplying energy to the tube and the means for regulating the tension of the gas to which the energy is supplied. 85

In the foregoing description and in the claims appended, the term "gas" is to be understood as including the aeroform condition of any solid or liquid and commonly known as vapor. 90

The combination of a vacuum tube, a transformer and a valve controlling the feed of gas to the tube and responsive to changes in the magnetic condition of the transformer is not claimed herein as this organization of 95 devices is claimed in my co-pending application for patent filed Feb. 7th, 1906, S. N. 299,885.

While I have referred herein to the use of a tank in connection with the valve and 100 vacuum tube, the same organization is described in my application for patent filed Apr. 2nd, 1906, S. N. 309,283 and therefore no claim is made thereto in the present application. 105

What I claim as my invention is:

1. The combination of a vacuum tube, a valve chamber closed by a spring diaphragm, a valve acted upon by said diaphragm in a direction to keep the valve closed and means 110 responsive to changes in the gaseous condition within the tube for lifting the valve.

2. The combination of a vacuum tube, a valve controlling the supply of a gas to said tube, a valve chamber closed by a spring dia- 115 phragm which is connected to the valve and tends to keep the same closed and a transformer supplying energy to the tube and having a movable core connected with the valve and adapted to open the same by an increase 120 in the magnetic pull on said core.

3. The combination of a vacuum tube, a valve controlling the supply of a gas to said tube, a valve chamber closed by a spring dia- 125 phragm tending to keep the valve closed, a transformer and means responsive to changes in the magnetic condition thereof for actuating the valve to open the same and admit gas to the tube.

4. The combination of a vacuum tube, a 130

valve controlling the supply of gas to said tube, a valve chamber, a spring diaphragm closing the chamber and connected to the valve, and an actuating electro magnet operating on the diaphragm and valve in response to changes in the electrical resistance of the gas or vapor within the vacuum tube.

Signed at New York in the county of New York and State of New York this 22d day of January A. D. 1906.

DANIEL MCFARLAN MOORE.
